UNITED STATES PATENT OFFICE.

ARTHUR LEONARD PERHAM, OF EAST MOSELEY, ENGLAND, ASSIGNOR TO VICKERS LIMITED, OF WESTMINSTER, LONDON, ENGLAND.

LEVEL-CORRECTION DEVICE FOR ORDNANCE.

Application filed June 8, 1923. Serial No. 644,118.

To all whom it may concern:

Be it known that I, ARTHUR LEONARD PERHAM, a subject of the King of Great Britain, residing at The New House, 8 Matham Road, East Moseley, in the county of Worcester, England, have invented certain new and useful Improvements in or Relating to Level-Correction Devices for Ordnance, of which the following is a specification.

This invention relates to level correction devices for ordnance, particularly guns for anti-aircraft or coast defence mounted on portable or automobile carriages. Such gun carriages are often required to be placed on ground that does not afford a level or constantly rigid support, and it is necessary for accurate shooting to provide means for levelling the gun mounting itself so as to bring 20 the training axis into a truly vertical position, or for adjusting the sighting apparatus to compensate for the inclination of the training axis of the gun from the vertical. If the gun is other than a very light one it 25 is not practicable, owing to the weight of the parts, to provide means for maintaining its training axis vertical, and the object of the present invention is to provide an improved correction device by which errors in 30 the aiming of the gun due to the lack of level of the gun carriage can be neutralized or compensated for without the gun mounting itself requiring to be levelled.

In gun mountings to which the invention 35 is particularly applicable, the gun is usually laid in elevation and training by means of pointers or other members set to scales of elevation (or range) and of angles of training; alternatively the said pointers are arranged to turn on axes concentric with other 40 pointers under the control of a distant sighting apparatus on the well known "follow-the-pointer" system, or a pointer (one for elevation and one for training) under the 45 conjoint influence of the distant sighting apparatus and the gun may be employed, the pointer being maintained opposite a fixed mark as is well understood.

According to the invention the pointer or 50 other member by which the gun is laid either in elevation or in training is connected to a spirit level or its equivalent in such a manner that when the level is brought horizontal an adjustment will be given to the pointer so as to compensate for the er-

ror due to the tilt of the training axis. For example, in the case of elevation the gun elevation dial might be arranged to rotate once for 60° of gun elevation. In this case the level would be coupled to the gun elevation pointer so that each degree of angular movement of the level would effect 6° of angular movement of the said pointer. In the case of the gun training pointer, the level correction is applied through a variable-ratio device the ratio of which is adjusted in accordance with the gun elevation. This is necessary because the lateral error due to the inclination of the gun trunnions varies with the angle of gun elevation. At 45° of gun elevation the inclination of the trunnions requires a training correction of an amount equal to this inclination and at higher or lower elevations the correction is increased or reduced in proportion to the tangent of the angle of gun elevation.

By the use of the invention as hereinbefore described guns may be laid in accordance with angles transmitted from a distant or separate sighting station without the lack 80 of level of the mountings introducing inaccuracy in the shooting, but it is necessary that at every angle of gun training the level appertaining to the gun elevation pointer and the gun training pointer should be readjusted, because the effect of a tilted training axis varies with the training angle of the gun as measured from the direction in which the axis is tilted. To obviate the necessity for such continual adjustment of the levels, 90 the levels may be connected to crossheads free to slide in directions at right angles to each other, in which crossheads a crank pin engages. If this crank pin is adjusted in radius to correspond with the angle of inclination of the training axis and if it is adjusted relatively to the angle of gun training so that the rotation of the member carrying it is in phase with the angles of the gun training in relation to that angle of training 95 in which the training axis is tilted, then at all angles of training the levels will be adjusted automatically by the crank pin to maintain their horizontal positions. To enable the crank pin to be thus set to the 100 amount and angular position of the tilt of the training axis the crank pin may project from a disc or block capable of being moved to any position on the face of the aforesaid rotatable member. Thus if at any angle of 105

gun training the two levels are adjusted to a horizontal position the two crossheads will cause the crank pin to take up a position on the said rotatable member corresponding to 5 the amount and direction of the tilt of the gun training axis. If the crank pin is now locked to the rotatable member, then at all training angles it will keep the two levels horizontal.

10 The invention is also applicable to gun sighting apparatus that is combined with the gun mounting, its mode of application varying with the type of sighting apparatus in use. As applied to gun sighting apparatus combined with the mounting it is generally only the training that requires correction and the invention would then be applied to the lateral deflection dial.

15 A common type of levelling arrangement 20 is that in which the sighting apparatus is pivoted about an axis parallel to the axis of the gun and is levelled about this axis. Such a levelling arrangement is open to the objection that releveling is necessary with 25 every change in gun training and to avoid this necessity the automatic levelling feature of the invention can be applied to such devices. For example a crank pin can be positioned by the two levels and crossheads 30 as hereinbefore described and be so connected to the sighting apparatus that during the training of the gun the said crank will automatically level the sighting apparatus about its axis parallel to the axis of 35 the gun.

40 In order that the said invention may be clearly understood and readily carried into effect, the same will now be described more fully with reference to the accompanying drawings, in which:—

45 Figure 1 is a side elevation shewing diagrammatically a simple form of the correction device applied to the elevation pointer of a gun,

50 Figure 2 is a section taken approximately on the line 2, 2 of Figure 1,

55 Figure 3 is a side elevation shewing diagrammatically a form of the correction device applied to the elevation and training pointers of a gun, in conjunction with an arrangement by which the corrections are effected automatically at all angles of elevation and training so long as the tilt of the training axis remains the same,

60 Figure 4 is a section taken approximately on the line 4, 4 of Figure 3,

65 Figure 5 is a front elevation of part of Figure 3,

70 Figure 6 is a view similar to Figure 3 shewing the correction device employed for automatically levelling a gun sight, and

75 Figure 7 is a rear elevation of Figure 6.

80 Referring first to Figures 1 and 2, A represents the elevation dial connected to a pinion α meshing with the elevating rack α'

85 of the gun, B represents the "reader" or pointer associated with this dial and C represents the level the support C' of which is pivoted at c to a bracket c' on the gun carriage and has a toothed segment C² meshing with a pinion b connected to the pointer B. It is essential that the same gear ratio shall exist between the support C' and the pointer B as exists between the gun and the dial A. It will therefore be seen that if the training axis of the gun is inclined to the vertical in a direction affecting the correct elevation of the gun, the bringing of the level C to the horizontal will vary 90 the position of the pointer B by an amount sufficient to compensate for the elevation error caused by the tilt of the training axis at the particular angle of training existing at the moment. If the angle of tilt remains constant and the angle of training is altered, the level C will require readjustment to maintain it horizontal in this particular construction. A similar arrangement may be employed in conjunction with the training pointer (the level being situated at right 95 angles horizontally to the level C) but in this case the correction is applied from the level carrier to the training pointer through a variable-ratio device, such as is hereinafter described, the ratio of which is adjusted in accordance with the gun elevation for the 100 reason hereinbefore referred to.

105 In the construction shewn by Figures 3, 4 and 5 the elevation dial A and the pointer B are geared to the elevating rack α' of the gun and to the level support C' respectively in substantially the manner described with reference to Figures 1 and 2. The level support C' is adjusted about its pivot c by a bar D which is free to slide vertically in 110 guides and carries at its lower end a cross-head d. This crosshead can be adjusted vertically by means of a handwheel D' and pinion d', the latter gearing with rack teeth on the bar D. Another level E (Figure 5) at right angles to the level C in the horizontal 115 plane, is carried by a support E' pivoted at e on the gun carriage. This level is adjusted about its pivot by a bar F through a bell crank lever F^x and a link f^x. The said bar is free to slide horizontally in guides and carries at one end a crosshead f which can be adjusted horizontally in a similar manner to the crosshead d by means of a handwheel F' and pinion f'. The said crossheads engage 120 with a pin g in the centre of a disc G (Figure 4). This pin passes through the disc and engages on the other side with friction discs G'. The discs G and G' are assembled in alternate layers with friction 125 washers g'. The whole thus assembled is contained in a casing G² by means of a cover g² which exerts sufficient pressure between the various contacting faces to frictionally grip the crank pin disc G in any 130

desired position to which it is set by means of the handwheels D' and F'. The casing G² is suitably geared to the training rack of the gun mounting so that it rotates with, 5 and at the same angular velocity as, the mounting. The pin g thus conveys motion, by reason of its eccentricity, through the crosshead d and the bar D to the pointer B of the elevation dial A, and through the 10 crosshead f and the bar F to the bar H of a variable-ratio device and thence to a differential gear h which operates the pointers H' of a training receiver.

The aforesaid variable-ratio device 15 through which the corrections are made to the pointers H' of the training receiver is necessary on account of the fact that the lateral error due to the inclination of the gun trunnions varies with the angle of the 20 gun elevation. Therefore, the amount of correction applied must be variable accordingly. This is obtained as follows:—The bar H is supported by a pin h² in the extension of a rack H² operating upon the differential gear h and has a movable fulcrum h³ which is capable of being set to a scale H³ of gun elevations. The lower end of the said bar is forked and engages with a pin f² on the bar F. The latter bar in its 25 backward and forward movements oscillates the bar H about its fulcrum h³ and transmits movement to the rack H² varied in magnitude according to the gun elevation, i. e., according to the position of the 30 fulcrum h³ relatively to the pins h² and f². It will be seen that by the operation of the two handwheels D', F' each level is brought to the horizontal, the resistance of the friction plates G', g' overcome, and the 35 crank pin g by this operation correctly positioned according to the amount and direction of the tilt of the training axis so that the correct compensation will be given to the pointers B and H' at all angles of training. 40 Should the operator notice that the levels are no longer maintaining the horizontal position during change of the angle of training, then he knows that the inclination of the training axis has changed and he again adjusts 45 the levels to the horizontal by the handwheels D' and F', thereby impressing a new setting upon the crank pin g to suit the changed conditions of tilt. The duty of the operator is merely one of supervision of the 50 levels and re-adjustment of them as necessary. The fact that the levels and the operator move with the gun in training is an advantage that the invention possesses over mountings in which the axis of training is 55 itself adjusted to the vertical position.

When the invention is used in conjunction with an elevation receiver adjustable from a distant station in accordance with the angles of elevation to be given to the gun, the 60 bar D of Figures 3 to 5 and the level support

C' of Figures 1 and 2 would be connected to the equivalent of the pointer B through a differential gear.

In Figures 6 and 7, K is the gun sight the bracket k of which is connected to a 70 shaft K' rotatably supported in bearings k', k' on the gun cradle so that the said shaft lies parallel to the axis of the gun at all angles of elevation. In employing the automatic arrangement shewn in Figures 3 75 to 5 for rocking the shaft K' the following modifications are made, the same reference letters as are used in Figures 3 to 5 being also used for similar parts in Figures 6 and 7. The level support C' has a slotted end 80 with which a pin d^x on the bar D engages, the level support E' also has a slotted end with which a pin f^x on the bar F engages and the casing G² (together with the parts contained therein) is arranged horizontally 85 instead of vertically as in Figures 3 to 5. The elevation dial A and pointer B are dispensed with, the bar D being merely employed for the purpose of assisting in the correct positioning of the crank pin g. The 90 pivot pin e of the level support E' is rigid with the latter and extends forwardly through a bearing E² on the gun trunnion. This extension of the pivot pin is made to form one half of a Hooke's joint E³ the other 95 half of which forms part of the aforesaid shaft K'. The axis of the pivotal connection e³ of this universal joint is arranged to be in alignment with the axis of the gun trunnions. In operation, the two levels 100 having been adjusted by their respective handwheels and the crank pin g set to its correct position relative to the angle of training in which the vertical axis of the mounting is tilted and to the magnitude 105 of such tilt, the pivot pin e is always kept cross levelled by the movement of the bar D and this correction is transmitted through the Hooke's joint E³ to the gun sight. So long as the gun is kept horizontal and the 110 sight and the shaft K' therefore parallel to the pivot pin e, both halves of the Hooke's joint will move together and through the same angle, but as the gun is elevated the shaft K' moves with it whilst 115 leaving the pivot pin e in its original position. The movement imparted to the gun sight through the Hooke's joint is therefore increased in the inverse proportion of the cosine of the angle of elevation. In this 120 manner the Hooke's joint functions as a variable-ratio device and with the added correction derived from the range setting of the sight replaces the variable-ratio device described in connection with Figures 125 3 to 5.

What I claim and desire to secure by Letters Patent of the United States is:—

1. A level correction device for ordnance, comprising in combination a member by 130

- which the gun is laid, a levelling element and a connection between said member and said element operating to adjust said member to compensate for the error due to the 5 tilt of the training axis of the gun.
2. A level correction device for ordnance, comprising in combination a member by which the gun is laid in elevation, a levelling element and a connection between said 10 member and said element operating to adjust said member to compensate for the elevation error due to the tilt of the training axis of the gun.
3. A level correction device for ordnance, 15 comprising in combination a member by which the gun is laid in training, a levelling element and a connection between said member and said element operating to adjust said member to compensate for the 20 training error due to the tilt of the training axis of the gun.
4. A level correction device for ordnance, 25 comprising in combination a member by which the gun is laid in elevation, a member by which the gun is laid in training, a levelling element, a connection between said levelling element and the first mentioned member, a second levelling element, and a connection between the latter levelling element 30 and the second mentioned member.
5. A level correction device for ordnance, comprising in combination an elevation indicator composed of two movable members, mechanism for operating one of said members in accordance with the elevating movements of the gun, a levelling element and mechanism interposed between said element and the other member of the indicator, the last mentioned mechanism having the same 40 gear ratio as that of the first mentioned mechanism.
6. A level correction device for ordnance, 45 comprising in combination a member by which the gun is laid in training, a levelling element, connections between said member and said element and a variable ratio device forming part of said connections.
7. A level correction device for ordnance, 50 comprising in combination a member by which the gun is laid in training, a levelling element, connections between said member and said element, a fulcrumed lever forming part of said connections and means for adjusting said fulcrum to agree with the 55 gun elevation.
8. A level correction device for ordnance, 60 comprising in combination a member by which the gun is laid in elevation, a member by which the gun is laid in training, a levelling element, a connection between said levelling element and the first mentioned member, a second levelling element, a connection between the latter levelling element 65 and the second mentioned member, and means for automatically maintaining said 70 elements in their levelled position during the training of the gun so long as the tilt of the training axis of the gun remains unaltered.
9. A level correction device for ordnance, 75 comprising in combination a member by which the gun is laid in elevation, a member by which the gun is laid in training, a levelling element, a connection between said levelling element and the first mentioned member, a second levelling element, a connection between the latter levelling element and the second mentioned member, an adjustable member, means for connecting said adjustable member to said levelling elements 80 and means for rotating said member in synchronism with the training of the gun.
10. A level correction device for ordnance, 85 comprising in combination a member by which the gun is laid in elevation, a member by which the gun is laid in training, a levelling element, a connection between said levelling element and the first mentioned member, a second levelling element, a connection between the latter levelling element 90 and the second mentioned member, a crank pin, a member carrying said crank pin, guided bars connected to said levelling elements, said crank pin engaging in slots formed in said bars at right angles to the 95 paths of movement of the latter, and means for rotating said member in synchronism with the training of the gun.
11. A level correction device for ordnance, 100 comprising in combination a member by which the gun is laid in elevation, a member by which the gun is laid in training, a levelling element, a connection between said levelling element and the first mentioned member, a second levelling element, a connection between the latter levelling element 105 and the second mentioned member, a crank pin, a member carrying said crank pin, guided bars connected to said levelling elements, said crank pin engaging in slots 110 formed in said bars at right angles to the paths of movement of the latter, a further member, means for rotating the latter member in synchronism with the training of the gun and means for frictionally holding the 115 last two mentioned members in operative connection with each other.
12. A level correction device for ordnance, 120 comprising in combination with the gun sight, two levelling elements arranged to move in vertical planes at right angles to each other, means for automatically maintaining said elements in their levelled position during the training of the gun so long as the tilt of the training axis of the gun 125 remains unaltered and means operated by the first mentioned means for rocking the sight about a longitudinal axis parallel to the axis of the gun barrel.
13. A level correction device for ordnance, 130

48

1,484,274

5

comprising in combination with the gun sight, two levelling elements arranged to move in vertical planes at right angles to each other, an adjustable member, means for connecting said member to said levelling elements, means for rotating said member in synchronism with the training of the gun and means whereby the rotation of said member automatically rocks the sight about a longitudinal axis parallel to the axis of 10 the gun barrel.
